UNITED STATES PATENT OFFICE.

WILLIAM M. NORCROSS, OF PHILADELPHIA, PENNSYLVANIA, ASSIGNOR TO THE HALE & KILBURN MANUFACTURING COMPANY, OF PENNSYLVANIA.

FOOT-REST FOR CAR-SEATS.

SPECIFICATION forming part of Letters Patent No. 605,124, dated June 7, 1898.

Application filed July 28, 1897. Serial No. 646,165. (No model.)

To all whom it may concern:

Be it known that I, WILLIAM M. NORCROSS, of the city and county of Philadelphia, State of Pennsylvania, have invented an Improvement 5 in Foot-Rests for Car-Seats, of which the following is a specification.

My invention relates to foot-rests for car-seats; and it consists of the improvements which are fully described in the following 10 specification and are shown in the accompanying drawings.

It is the object of my invention to provide a foot-rest for a car-seat of such a character that it will leave the front portion of the floor 15 space below the seat free and unobstructed, so that it may be used for stowing away baggage and packages.

It is also an object of my invention to provide a rocking foot-rest of such character 20 that it may be rocked to lower the bar in the rear of the seat in position to act as a foot-rest for the occupants of the rear seat and to elevate the bar at the front of the seat, so as 25 to leave the floor-space clear, and to lock the rear bar at a slight distance above the floor, so that it cannot be further lowered from the rear.

In carrying out my invention I support 30 a rocking-foot-rest frame upon supports by means of a fulcrum, having provision for automatically locking the lowered end of the rocking-foot-rest frame against further downward movement when it has descended to a given extent.

35 In the preferred embodiment of my invention I support the foot-rest frame upon the supports, on which it rests and is adapted to rock by means of supporting pins or lugs engaging trifurcate slots or grooves.

40 In the drawings, Figure 1 is an end elevation of a car-seat embodying my invention. Fig. 2 is a horizontal sectional view of the same on the line $x-x$ of Fig. 1, and Fig. 3 is a transverse vertical sectional view on the line 45 $y-y$ of Fig. 3.

A A are the usual side frames, which may be of any suitable construction.

B is the rocking foot-rest, which consists of two longitudinal bars C C', carried by cross-bars or levers D D, and so located that one 50 of the longitudinal bars or rests C C' will be

on each side of the seat-frame. The cross-bars or levers D D are located one at each end and are supported by suitable frames or supports carried by the end frames, upon which 55 they are adapted to rock.

In the construction illustrated in the drawings I have shown the support for the cross-bar or lever D at the inner end of the seat composed of a transverse frame E, supported 60 by the longitudinal rails F F of the seat-frame, while the pedestal G of the outer side frame constitutes the support for the cross-bar or lever D at the outer end of the seat. This construction may, however, be varied, 65 as the particular arrangement or location of the support is not material.

Each of the supports for the cross-bars or levers D D is provided with a trifurcate groove or slot H, having one arm a extending 70 upward and the two arms b c extending downward therefrom, one on each side.

The bars or levers D D are provided with two lugs, pins, or projections d e , one above the other and so arranged and located that 75 when the upper projection d is in the upwardly-extending portion a of the slot H the lower projection e will be in either one of the downwardly-extending portions b c of the slot H. From this it results that the frame 80 of the foot-rest B will normally occupy an inclined position, with one bar elevated so as to be immediately below the seat-frame and the other lowered so as to be near the floor, and thus constitute a rest for the feet of the 85 occupants of the rear seat. The foot-rest is automatically locked in this position against further descent, since any effort to further depress the rear bar (C' in Fig. 1) will simply force the pins d e against the walls of the 90 grooves a b .

The foot-rest B may, however, be readily rocked by lowering of the front bar (C in Fig. 1) or by lifting the bar C', which will cause the pin d to rise in the groove a , while the pin e rides up through the groove b 95 and passes into the groove c , into which it descends, the pin d correspondingly descending again into the groove a . The angular position of the foot-rest is then reversed, with the bar C' elevated and the bar C lowered, 100 and in this position it is again automatically locked against further descent. The trifur-

cate groove or slot II and the pins *d e* thus constitute an automatically-locking fulcrum, which locks the foot-rest frame against further downward movement on the fulcrum 15 and sustains the lowered bar in a more or less raised position above the floor. The lowered foot-rest will thus be maintained firmly in position as a support for the feet, and as the opposite bar is elevated under the seat it will not be in position to be accidentally moved. When the seat-back is shifted, the foot-rest may be rocked so as to bring the lowered bar at the rear of the seat.

As the bar at the front is elevated the space 15 below the front of the seat is left open and unobstructed to receive packages and baggage, thus avoiding the obstruction of the floor-space in front of the seat.

While I prefer the details of construction 20 that have been shown, it is apparent that they may be varied without departing from the invention.

What I claim as new, and desire to secure by Letters Patent, is as follows:

1. In a car-seat, the combination with end 25 supports, of a rocking-foot-rest frame, and connecting supporting devices between the rocking-foot-rest frame and the end supports, consisting of a trifurcate groove or slot on the end support and a pair of pins or projections on the foot-rest frame adapted to engage simultaneously two arms of the trifurcate groove or slot.

2. In a car-seat, the combination with end supports each provided with a trifurcate slot 35 or groove II, of a rocking-foot-rest frame B, composed of two longitudinal foot-rest bars C, C', and cross-bars D, D each provided with projections *d e*, adapted to engage the trifurcate grooves or slots II, substantially as and 40 for the purposes described.

In testimony of which invention I hereunto set my hand.

WM. M. NORCROSS.
